UNITED STATES PATENT OFFICE.

LAWRENCE E. SCRANNAGE, OF PHILADELPHIA, PENNSYLVANIA.

CARBURETOR.

Application filed December 11, 1920, Serial No. 429,979. Renewed April 14, 1924.

To all whom it may concern:

Be it known that I, LAWRENCE E. SCRANNAGE, a citizen of the United States, residing at Philadelphia, in the county of Philadelphia and State of Pennsylvania, have invented new and useful Improvements in Carburetors, of which the following is a specification.

This invention relates to improvements in carburetors for internal combustion engines, the principal object of the invention being to provide means for igniting a mixture of gas and air in a combustion chamber and introducing the products of combustion from this chamber into the explosive charge as it leaves the carburetor so that less volatile liquids may be used for running the motor.

Another object of the invention is to provide an auxiliary air supply, with means for mixing the quantity of fuel therewith and means for drawing on said supply when the motor reaches a high speed.

Another object of the invention is to provide means for circulating hot water or hot air through the carburetor to heat the mixture passing through the Venturi tube.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a plan view of the invention.

Figure 2 is a longitudinal section on line 2—2 of Figure 1.

Figure 3 is a section on line 3—3 of Figure 1.

Figure 4 is a section on line 4—4 of Figure 1.

Figure 5 is a section on the line 5—5 of Figure 1.

Figure 6 is a horizontal section on the line 6—6 of Figure 2.

Figure 7 is a detail vertical sectional view showing the modification of the means for supplying fuel mixture to the combustion chamber.

Figure 8 is a sectional detail view showing a wire, adapted to be heated by electricity, used instead of a spark plug.

Figure 9 is a diagrammatic view showing a method of heating the carburetor by hot air.

Figure 10 is a modification for heating the carburetor by hot water.

In these views 1 indicates the body of the carburetor in which is located the Venturi tube 2, the outlet end of which is controlled by the usual butterfly valve 3 which is actuated from a point adjacent the driver's seat in any desired manner. The nozzle 4 and needle valve 5 are also arranged in the usual or any desired manner and the air supply to the Venturi tube is controlled by the spring controlled choke valve 6, this valve being also arranged to be operated by means leading to a point adjacent the driver's seat as will be understood. The nozzle 4 is connected by a passage 7 with the float chamber 8, said chamber being connected with the source of supply by connection 9 and tube, not shown. A float 10 is located in the chamber and this float is adapted to close the spring controlled valve 11 through means of the dogs 12 which are carried by the adjustable sleeve 13. From this construction it will be seen that as the float is forced upwardly by the liquid it will cause the dogs to press the stem 14 against the valve 11 so as to seat the same and thus close the connection between the float chamber and the supply tank.

The suction created by the moving pistons will act to draw the fuel from the float chamber through the nozzle and this liquid will be mixed with the air sucked in past the valve 6. This action is similar to the action taking place in carburetors now in use.

I also provide an auxiliary air supply with means for mixing liquid fuel therewith, which is rendered active when the engine reaches a high speed. Such means comprises a casing 15 which is connected with the body 1 and the interior of which is in communication with the space within the tube 2 by means of the ports 16 and the interior of this casing is also in communication with the atmosphere by means of the opening 17. This opening is normally closed by the spring controlled valve 18. However, when the action reaches a certain speed so that a certain suction is created, this suction will open valve 18 to permit the atmospheric air to pass through opening 17 into the casing and from the casing through

ports 16 into the carburetor. The means for mixing the liquid fuel with this incoming air consists of a wall 19 of the carburetor which has a U-shaped passage 20 there-
5 in, one end of which opens out into the Venturi tube 2 between the ports 16 while the other end is connected with the atmosphere. The bottom of this U-shaped passage is connected with an extension 7' of passage 7
10 which leads to the float chamber.

It will thus be seen that the suction created by the engine within the carburetor acts to draw air and fuel through said tube 19 and this mixture will commingle with the
15 air passing through casing 15. The amount of air passing through tube 19 can be controlled by the adjusting screw 21.

A combustion chamber 22 is formed in the upper part of said body 1 and a passage
20 23 leads from passage 7' to this chamber. A ball valve 24 is arranged in said passage 23 and an air passage 25 has its lower end connected with the passage 23 and its upper end extending through the exterior wall of
25 the casing so as to permit atmospheric air to enter the passage 23 and mix with the fuel passing upward therethrough. I may also provide a second air passage 26 which is connected with the upper end of passage 23 at
30 the point where it enters the chamber and this second passage is controlled by the adjustable valve 27 as shown in Figure 7. The mixture in the combustion chamber is ignited by means of the spark plug 28 which is
35 suitably connected with the electric circuit or by a wire coil 29 as shown in Figure 8 which is also adapted to be connected with the electric circuit. If this coil is used it may be placed in a porcelain sleeve 30 as
40 shown in Figure 8. The chamber 22 is connected by port 31 with the outlet of the Venturi tube 2 and this port is controlled by means of valve 32. This valve is actuated from a point adjacent the driver's seat
45 through the lever 33, flexible connection 34 and the hand lever 35 which is located in the casing 36. This hand lever 35 may also control the circuit to the spark plug 28 or to the coil 29 as shown diagrammatically at 37.
50 The parts would be so arranged that when

valve 32 is closed by handle 35 the circuit would be broken and when the handle 35 is moved to open valve 32 the circuit would be closed.

It will thus be seen that when desired a 55 supply of heated air can be mixed with the explosive charge on its way to the cylinder so that the charge can be easily exploded in the cylinders. This supply of heated air can be cut off after the engine has warmed 60 up if desired.

The combustion chamber 22 can be connected with the space 38 which surrounds the Venturi tube 2 so as to heat said tube or said combustion chamber can be separated 65 from this space by the partition 39, as shown in Figure 6. Figure 9 shows the Venturi tube 2 as being adapted to be heated by hot air, which is supplied in any desired manner to the inlet port 40 and which may be 70 fed into the tube through the opening 41 which is controlled by the spring valve 42.

Fig. 10 shows the tube being adapted to be heated by hot water, the supply pipe of which is connected with the inlet port 40' 75 and an outlet pipe 41' carries the water back to the heating means.

While I have shown the main part of the combustion chamber at the upper part of the carburetor it will of course be understood 80 that it may be located in any other desired place and it will also be understood that other means may be used for igniting the charge within the combustion chamber than those shown.

85 What I claim is:

A carburetor of the class described comprising a mixing chamber, a combustion chamber associated therewith, a high speed air inlet, a spring valve controlling the 90 same, a wall of the carburetor having a U-shaped passage therein which is connected with the fuel conduit of the carburetor, the inlet of said passage being arranged in the path of the high speed air supply and the 95 outlet therefrom opening into the combustion chamber in alignment with said inlet.

In testimony whereof I affix my signature.

LAWRENCE E. SCRANNAGE.
